CLAIM

The ornamental design for a shade for child car seat, as shown and described.

DESCRIPTION

FIG. 1 is a perspective view of a first embodiment of a shade for child car seat of the claimed design, shown mounted on a child car seat;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top elevational view thereof;

FIG. 7 is a bottom elevational view thereof;

FIG. 8 is a perspective view of a second embodiment of a shade for child car seat of the claimed design, shown mounted on a child car seat;

FIG. 9 is a front elevational view thereof;

FIG. 10 is a back elevational view thereof;

FIG. 11 is a right side elevational view thereof;

FIG. 12 is a left side elevational view thereof;

FIG. 13 is a top elevational view thereof; and,

FIG. 14 is a bottom elevational view thereof.

The features shown in broken lines are environment only and not part of the claimed design.
